UNITED STATES PATENT OFFICE.

RICHARD D. KNIGHT, OF PROVIDENCE, RHODE ISLAND.

DESIGN FOR A COMBINATION PAPER-CUTTER AND BOOK-MARK.

49,900.

Specification for Design. Patented Nov. 14, 1916.

Application filed July 12, 1916. Serial No. 108,963. Term of patent 3½ years.

To all whom it may concern:

Be it known that I, RICHARD D. KNIGHT, a citizen of the United States, residing at the city and county of Providence, State of Rhode Island, have invented a new, original, and ornamental Design for a Combination Paper-Cutter and Book-Mark, reference being had to the accompanying drawing, forming a part thereof.

The figure is a plan view of a combina-

tion paper cutter and book-mark illustrating my new design.

I claim:

The ornamental design for a combination paper cutter and book-mark as shown.

RICHARD D. KNIGHT.

Witnesses:

HORATIO N. OTIS,
ARTHUR L. DEAN.
